US00D918204S

(12) **United States Design Patent** (10) Patent No.: **US D918,204 S**
Raken et al. (45) Date of Patent: ** *May 4, 2021

(54) **ELECTRONIC INPUT DEVICE**(71) Applicant: **Microsoft Corporation**, Redmond, WA (US)(72) Inventors: **Jan Raken**, Seattle, WA (US); **Scott Schenone**, Seattle, WA (US); **Tim Escolin**, Seattle, WA (US)(73) Assignee: **Microsoft Corporation**, Redmond, WA (US)

(*) Notice: This patent is subject to a terminal disclaimer.

(**) Term: **15 Years**(21) Appl. No.: **29/737,910**(22) Filed: **Jun. 12, 2020****Related U.S. Application Data**

(62) Division of application No. 29/581,070, filed on Oct. 14, 2016, now Pat. No. Des. 890,754.

(51) **LOC (13) Cl.** ..... **14-02**(52) **U.S. Cl.**USPC ..... **D14/388**(58) **Field of Classification Search**

(57) **CLAIM**

The ornamental design for an electronic input device, as shown and described.

DESCRIPTION

FIG. 1 is a top front perspective view of an electronic input device showing our new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.
